INVENTOR.

F. L. Swenson,

BY

Geo. P. Kimmel. ATTORNEY.

UNITED STATES PATENT OFFICE.

FRITZ L. SWENSON, OF NORTHFIELD, VERMONT.

STENCIL.

Application filed February 10, 1923. Serial No. 618,296.

To all whom it may concern:

Be it known that I, FRITZ L. SWENSON, a citizen of the United States, residing at Northfield, in the county of Washington and State of Vermont, have invented certain new and useful Improvements in Stencils, of which the following is a specification.

This invention relates to stencils for stenciling letters or digits, and has for its object to provide in a manner as hereinafter set forth, a stencil body of a contour similar to a letter or digit and having means extended from said body to provide for the convenient holding of the same in position when tracing around the letter or digit, as well as enabling the letter or digit to be placed against a T-square whereby a plurality of letters or digits when in such position are arranged in a perpendicular line with respect to the T-square, and to further set up a stencil body capable of being positioned in a manner to enable one to trace around the same reversed, to provide a tracing which can be employed in connection with sand blast for stone work.

Further objects of the invention are to provide a stencil which is simple in its construction and arrangement, strong, durable, compact, efficient and convenient in its use, and inexpensive to manufacture.

With the foregoing and other objects in view, the invention consists of the novel construction, combination and arrangement of parts, as hereinafter more specifically described and illustrated in the accompanying drawings, wherein is shown an embodiment of the invention, but it is to be understood, that changes, variations and modifications can be resorted to which fall within the scope of the claims hereunto appended.

In the drawings:—

Figure 1 is a front elevation of a stencil body, in the form of a letter, in accordance with this invention.

Fig. 2 is a like view, of a modified form.

Fig. 3 is a vertical sectional view of the form shown in Fig. 2.

Figs. 4 to 7 are front elevations of modified forms of stencil bodies, of the digit type, in accordance with this invention.

Fig. 8 is a modified form of stencil body, of the letter type.

Referring to Fig. 1 of the drawings, the stencil body 10, is in the form of the letter A and which has extending from the apex

thereof a retaining projection in the form of a T consisting of a pair of arms 11, 12. The arm 11 is disposed centrally with respect to the arm 12 and extends at right-angles thereto. The arm 11 is integral with the body 10. Extending from the lower termini of the legs of the body 10, is a retaining projection in the form of a U and which consists of an arm 13 and a pair of arms 14, 15, which are disposed at right-angles with respect to the arm 13. The arms 14, 15 are arranged at the termini of the arm 13 and are also formed integral with the legs of the body 10. The arm 11 is of less width than the arm 12, and the arm 13 is of greater width than the arms 14, 15. The arm 11 is substantially of the same width as the arms 14, 15.

Referring to Figs. 2 and 3 of the drawings, the stencil body, which is indicated at 16, is in the form of the letter B and which has formed integral with the top thereof a retaining projection in the form of a U consisting of an arm 17 and a pair of arms 18, 19. The arms 18, 19, are disposed at right-angles with respect to the arm 17 and arranged integral with the termini of said arm 17 and are also integral with the body 16. The arms 18, 19 are of less width than the arm 17. Formed integral with the bottom of the body 16, is a retaining projection in the form of a U consisting of an arm 20 and a pair of arms 21, 22, which are disposed at right-angles with respect to the arm 20, are formed integral with the termini of the arm 20 and are also integral with the body 16. The arms 18, 19, are of less width than the arm 17 and the arms 21, 22, are of less width than the arm 20.

Referring to Fig. 4 of the drawings, the stencil body is in the form of a digit 1 and is indicated by the reference character 23. Extending from the top of the body 23 is a retaining projection in a form of a T consisting of a pair of arms 24, 25. The arm 24 is disposed centrally with respect to the arm 25 and extends at right-angles thereto and said arm 24 is of less width than the width of the arm 25. The arm 24 is integral with the top of the body 23. Extending from the bottom of the body 23 is a retaining projection in the form of a T consisting of a pair of arms 26, 27. The arm 26 is integral with the body 23 and also integral with the arm 27. The arm 26 is disposed at right-angles with respect to the arm 27, and is inte-

gral with said arm 27 centrally thereof. The arm 26 is of less width than the width of the arm 27.

Referring to Fig. 5 of the drawings, the 5 stencil body is in the form of a digit 2 and is indicated by the reference character 28. Formed integral with the top of the body 28 is a retaining projection in the form of a **U** consisting of an arm 29 and a pair of 10 arms 30, 31, which are disposed at right-angles with respect to the arm 29 and formed integral with the termini of the latter. The arms 30, 31, are of less width than the arm 29. Formed integral with the bottom of 15 the body 28 is a retaining projection in the form of a **U** consisting of an arm 32, and a pair of arms 33, 34, which are disposed at rightangles with respect to the arm 32 and formed integral with the termini of the latter. The arms 33, 34, are integral with 20 the body 28 and are of less width than the width of the arm 32.

Referring to Fig. 6 of the drawings, the 25 stencil body is in the form of a digit 4 and is indicated by the reference character 35. Formed integral with the upper portion of the body 35 is a retaining projection in the form of a **T** consisting of a pair of arms 36, 37. The arm 36 is disposed at rightangles 30 with respect to and is integral centrally with the arm 37, and is of less width than the width of the arm 37. The arm 36 is integral with the body 35. Formed integral with and projecting from the lower portion of the 35 body 35 is a retaining projection in the form of an outer arm 38, and a pair of arms 39, 40, the latter being of less length than the former. The arms 39, 40 are disposed at rightangles with respect to the arm 38 and 40 are integral with the termini of the latter and said arms 39, 40 are also integral with the body 35. The arms 39, 40, are of less width than the arm 38.

Referring to Fig. 7, the stencil body is 45 in the form of a digit 7 and is indicated at 41. Formed integral with and projecting from the top of the body 41, is a retaining projection in the form of a **U** consisting of an arm 42 and a pair of arms 43, 44, which 50 are disposed at rightangles with respect to the arm 42 and are formed integral with the termini of the latter. The arms 43, 44, are integral with the body 41 and are of less width than the width of the arm 42. Formed 55 integral with and projecting from the bottom of the body 41 is a retaining projection in the form of a **T** consisting of a pair of arms 45, 46. The arm 45 is integral with the body 41 and also integral with the arm 46, centrally thereof, and said arm 45 is of less width than the arm 46.

Referring to Fig. 8 of the drawings, the 60 stencil body is indicated at 47, and is in the form of the letter **S**. Formed integral with 65 and projecting from the bottom of the body

47 is a retaining projection in the form of a **U** consisting of an arm 48 and a pair of arms 49, 50, which are disposed at right-angles with respect to the arm 48 and formed integral with the termini of the latter, and are furthermore formed integral with the body 47. The arms 49, 50 are of less width than the width of the arm 48.

The stencil body and its retaining projection or projections can be formed of any 70 suitable material of the desired thickness, preferably metal or fibre.

The stencil body is made flat on each side so that it may be traced around not only 75 in normal position, but in a position reversed 80 from normal when desired.

The employment of a stencil body in accordance with this invention materially lessens the work when positioning the latter 85 for stenciling purposes.

When using a stencil in accordance with this invention, to set up an inscription for a monument, which is to be lettered by what is known as the sand blast process, a heavy 90 coarse tracing paper is placed on the drafting table, and the stencils are then selected in the order that they are to be used and positioned on the paper with the lower projection resting firmly against a **T**-square. This provides for the stencils to be set in a 95 perpendicular position to the **T**-square and then by pressing downwardly on the projection or projections of the stencils, they are held in position while a soft lead pencil is used to trace around them. In this case 100 the stencil should be reversed or reading from right to left. After the inscription has been completed the paper is taken and laid face down on the stone where composition has been previously applied. After 105 rubbing the surface of the paper, the paper is removed and the inscription has been transferred to the composition.

When using the stencils for lettering a 110 monument, which is to be by a pneumatic tool, they are traced on a light piece of tracing paper in a manner as before stated, except that the stencils are placed to read from left to right.

When employed for show card work, the 115 stencils may be traced in the manner as hereinbefore stated, but reading from left to right. When the outline has been completed, the letter can be completed in any suitable manner, or in other words, the letter can be filled in in any manner desired.

The preferred embodiment of the invention is that as described and shown, but it is obvious that changes in the details of construction can be had without departing 120 from the spirit of the invention as claimed.

What I claim is:

1. A stencil character comprising an independently shiftable solid body portion of 130 a contour corresponding to the character,

- and having extended from one end thereof a spacing projection provided with a free outer terminus constituting a positioning medium for the body portion.
- 5 2. A stencil character comprising an independently shiftable solid body portion of a contour corresponding to the character, and having extended from one end thereof a spacing projection provided with a free 10 outer terminus constituting a positioning medium for the body portion, said projection formed of a plurality of arms.
- 15 3. A stencil character comprising an independently shiftable solid body portion of a contour corresponding to the character, and having extended from one end thereof a spacing projection provided with a free outer terminus constituting a positioning medium for the body portion, said projection formed of a plurality of arms disposed 20 at an angle with respect to each other.
- 25 4. A stencil character comprising an independently shiftable body portion of a contour corresponding to the character and having extended from one end thereof a spacing projection formed with a free outer terminus constituting a positioning medium for the body portion, said projection of yoke-shape.
- 30 5. A stencil character comprising an independently shiftable body portion of a con-
- tour corresponding to the character and having extended from one end thereof a spacing projection formed with a free outer terminus constituting a positioning medium for the body portion, said projection of yoke-shape and with the arms thereof integral with and of less width than the width of the body portion.
- 35 6. A stencil character comprising an independently shiftable body portion of a contour corresponding to the character and having extended from one end thereof a spacing projection formed with a free outer terminus constituting a positioning medium for the body portion, said projection of yoke-shape, said body portion further having extending from the other end thereof a T-shaped projection.
- 40 7. A stencil character comprising an independently shiftable body portion of a contour corresponding to the character, said body portion having extended from each end thereof a spacing projection formed with the free outer terminus constituting a positioning medium for the body portion, the projection at one end of the body portion being of a different contour from that at the other end of the body portion.
- 45 In testimony whereof, I affix my signature 50 hereto.
- 55 FRITZ L. SWENSON.
